UNITED STATES PATENT OFFICE.

LUKE L. KELLOGG, OF FREDONIA, NEW YORK.

AUTOMOBILE-LIFTER.

1,291,546.

Specification of Letters Patent. Patented Jan. 14, 1919.

Application filed November 15, 1918. Serial No. 262,675.

To all whom it may concern:

Be it known that I, LUKE L. KELLOGG, a citizen of the United States, residing at Fredonia, in the county of Chautauqua and State of New York, have invented a new and useful Automobile-Lifter, of which the following is a specification.

This invention relates to a lifter or jack for automobiles of that type adapted to elevate the automobile from the ground or floor by the force of the impact of the machine when driven into position above and in engagement with the apparatus. One of the objects of the invention is to provide a device of this character which is simple and inexpensive in construction, efficient in operation, and capable of adjustment to adapt it to machines of different sizes.

Another object is to provide a lifter or jack which can be adjusted to raise the engaged automobile a desired distance, means being provided for locking the lifter against retrograde movement.

With the foregoing and other objects in view the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth in the appended claims.

35 In the accompanying drawings the preferred form of the invention has been shown.

In said drawings,

Figure 1 is a side elevation of the device.

Fig. 2 is a central longitudinal section.

40 Fig. 3 is a plan view, a portion being shown in section.

Fig. 4 is a section on line 4—4, Fig. 2.

Fig. 5 is a section on line 5—5, Fig. 2.

Fig. 6 is a section on line 6—6, Fig. 2.

45 Referring to the figures by characters of reference, 1 designates side strips having longitudinal tongues 2 extending from one end thereof while the other ends of said side strips are connected by a cross strip 3 and a

50 top strip 4. The top strip 4 has a push bar 5 pivotally connected thereto at the center while the cross strip 3 is provided with an opening 6 at the bottom portion of which is arranged a holding plate or keeper 7.

55 A short rail 8 is arranged on the inner side

of each strip 1 and is pivotally connected to the strip as shown at 9, these rails extending forwardly toward the cross strip 3 and having studs 10 adapted to slide within arcuate slots 11 in the strips 1. Nuts 12 engage the 60 studs and by means thereof the rails can be fastened in any positions to which they may be adjusted angularly.

Wheels 13 are arranged under the rails and are connected by an axle 14 on which are 65 mounted spacing sleeves 15. A collar 16 is loosely mounted on the axle and between the sleeves and has a locking arm 17 extending therefrom and through the opening 6, there being ratchet teeth 18 on the lower face of 70 the arm and any one of which is adapted to engage plate 7.

The structure heretofore described constitutes the front section of the lifter or jack. The rear section of the device includes side 75 strips 19 having longitudinal slots 20 extending thereinto from one end while the other ends of the strips are connected by an end strip 21 and a top strip 22. On this top strip is arranged a centering or guide bar 23 the end portions of which converge forwardly as shown particularly in Fig. 3. Rails 24 are arranged on the inner faces of the strips 19 and are pivotally connected to said strips, as shown at 25, the other ends 80 of the rails being provided with studs 26 which slide within arcuate slots 27 and have nuts 28 whereby the said rails can be fastened at any positions to which they may be adjusted angularly. Wheels 29 are located 85 under the rails and are connected by an axle 30. The side strips 19 can be further connected and braced by a cross strip 31 secured to the lower edges thereof.

The tongues 2 are inserted into and slideable within the slots 20 and are held therein by side plates 32 secured to the strips 19 and extending across the slots 20, and by plates 33 secured to the tongues 2 andlapping the sides of the strips 19. A set screw 100 90 or the like is arranged in each strip 19 and is adapted to engage the tongue therein and lock the tongue against movement in the slot.

When it is desired to use the device the 105 wheels 13 and 29 are placed on the ground and under the rails 8 and 24 respectively, the front wheels abutting against the front strip 3 and the rear wheels against the strip 31. In both positions the wheels are under the 110

uppermost ends of the rails. The arm 17 is also projected its greatest distance through the opening 6. The several parts thus occupy the relative positions shown in Fig. 1. 5 The set screws 34 are loosened and the strips 1 and 19 are shifted relative to each other until the distance between the bar 5 and the middle portion of the bar 23 is equal to the distance between the axles of the machine 10 to be lifted. The set screws are then tightened and the device is ready for use.

The automobile is driven over the lifter and astride it. The front axle will strike against the bar 5 and the differential case 15 on the rear axle will come against the bar 23. If it is not in the center of the lifter, the inclined or oblique end of the bar 23 will deflect it toward the center. The impact of the machine will be sufficient to move 20 the sections forwardly so that the inclined rails 8 and 24 will ride on the wheels 13 and 29, at the same time drawing the arm 17 through the opening and causing certain 25 of the teeth 18 to slip over the plate 7. This movement will be sufficient to lift the wheels of the machine off of the ground where it will be held until the free end of arm 17 is lifted, whereupon the teeth will be disengaged and the lifter with the automobile 30 thereon, will gravitate back to its initial position. By providing angularly adjustable rails, the lifter can be caused to move upwardly at any angle desired.

It will be noted that cross strips 35 are 35 connected to the sides of the sections and across the paths of the wheels 13 and 29. These strips serve to engage the wheels and limit the movement of the lifter under the action of the automobile being elevated.

40 What is claimed is:

1. A device of the character described including a structure having angularly adjustable rails upon the sides thereof, supporting wheels connected in pairs and located under 45 and supporting the rails, and a toothed arm

connected to one pair of wheels and slideable in one direction in a wall of said structure.

2. A device of the class described including supporting wheels arranged in pairs, a structure having angularly adjustable side 50 rails resting on the peripheries of the respective wheels, and means connected to one pair of wheels and coöperating with said structure for holding the structure against movement in one direction upon the wheels. 55

3. A device of the class described including supporting wheels arranged in pairs, a structure having angularly adjustable side rails resting on the peripheries of the respective wheels, means for holding the rails against downward movement upon the wheels, a pivoted push bar upon one end of the structure, and a centering bar upon the other end of the structure and having forwardly converging end portions. 65

4. A device of the class described including adjustably connected front and rear sections, angularly adjustable rails upon the sides of each section, and wheels under the rails and having their peripheries in engagement therewith. 70

5. A device of the class described including interfitting, slidably connected front and rear sections, means for holding the sections against relative movement, angularly adjustable rails upon the sides of each section, wheels arranged in pairs under and supporting the respective rails, and coöperating means connected to the wheels of one section and to said section for holding the 80 rails against downward movement upon the wheels. 75

In testimony that I claim the foregoing as my own I have hereto affixed my signature in the presence of two witnesses.

LUKE L. KELLOGG.
